UNITED STATES PATENT OFFICE.

JAMES H. MILLER, OF ELLSWORTH, KANSAS.

HAYSTACKER.

Application filed July 28, 1924. Serial No. 728,699.

To all whom it may concern:

Be it known that I, JAMES H. MILLER, a citizen of the United States, residing at Ellsworth, in the county of Ellsworth and 5 State of Kansas, have invented a new and useful Haystacker, of which the following is a specification.

This invention aims to provide a hay stacker embodying novel means for raising 10 and lowering the track along which the hay fork, sling or other instrumentality which carries the hay, is adapted to move, it being possible, thus, to adjust the height of the track end of the fork or sling, as the stack 15 is built up.

It is within the province of the disclosure to improve generally and to enhance the utility of devices of that type to which the invention appertains.

20 Although a preferred form has been shown in the drawings, it will be understood that a mechanic, working within the scope of what is claimed, may make changes without departing from the spirit of the invention.

25 In the drawings:—Figure 1 shows in side elevation a device constructed in accordance with the invention; Figure 2 is an end elevation; Figure 3 is a section taken about on the line 3—3 of Figure 1, parts being left 30 in elevation; Figure 4 is a section taken approximately on the line 4—4 of Figure 1, parts being omitted; Figure 5 is a section taken approximately on the line 5—5 of Figure 1.

35 In carrying out the invention, there is provided a main frame 1 including corner posts 2 and 3 and intermediate posts 4 which may be channel members, although this detail is not insisted upon. The posts 2, 4 and 40 3 are connected at each side of the machine by longitudinal upper bars 6 and by lower longitudinal bars 5. The posts 2—2, 4—4 and 3—3 are connected by transverse upper bars 7 and lower bars 8. The upper portions of the posts 2 and 3 are connected with the lower portions of the posts 5 by diagonal braces 9, the bars 6 overlapping the upper ends of the braces, and the bars 5 overlapping the lower ends of the braces, 45 if desired, as clearly indicated in the drawings.

50 Openings 10 are formed in the upper ends of the posts 2—4—3, and in the openings, pulleys 11 are located, the hubs 12 of the pulleys being attached by securing elements 14, such as set screws, to shafts 15 journaled

in the side flanges of the posts and in bearings 16 on the inner surfaces of the said flanges, the shafts 15 being insertable endwise into place, as will be understood readily 60 when Figure 3 of the drawings is noted.

Bearings 17 are mounted on posts 2—4—3, near to their lower ends, and project outwardly from the posts. In the bearings 17 at each side of the device, shafts 18 are 65 journaled. The shafts 18 carry drums 19, disposed between the bearings 17 of each pair, as Figure 4 will show. The ends of the shafts 18 which adjacent to the posts 2 are provided with operating means 20, which 70 may be cranks. Ratchet wheels 21 are secured to the shafts 18, outwardly of the posts 2, and are adapted to be engaged by pawls 22 mounted pivotally on brackets 23 projecting outwardly from the posts 2. 75 Flexible elements 24 are wrapped about the drums 19, the flexible elements extending upwardly over the pulleys 11, and thence downwardly, on the inside of the posts 2—4—3, as indicated in Figure 2. 80

Slides 25 are mounted for vertical reciprocation in the posts 2—3—4, each slide comprising a top member 26, having downwardly extended ends 27 prolonged to form upwardly inclined braces 28 joined by a connecting portion 29 secured at 30 to the intermediate portions of the top member 26. A track 31, of any desired construction, is secured to the parts 29 and 26 of the slides 25. A fork, sling, or other instrumentality 90 (not shown) for carrying hay or straw or the like, is adapted to move along the track 31 in a way well understood by those skilled in the art. The inner ends of the flexible elements 24 are secured by eye bolts 32, or in 95 any other appropriate way, to the top members 26 of the slides 25.

The shafts 18 may be rotated by means of the operating members 20, the pawls 22 cooperating with the ratchet wheels 21 to hold 100 the shafts 18 against reversed rotation. The flexible elements 24 may be wound upon or paid off the drums 19, to secure a raising or a lowering of the slides 25, along with the track 31, and in this way, the hay fork or 105 the like may be raised as the stack is built up.

What is claimed is:—

1. A hay stacker comprising posts, slides mounted for reciprocation on the posts, a 110 track carried by the slides, shafts extended between the posts and journaled thereon,

flexible elements connected at their ends to the shafts and to the slides and guided intermediate their ends on the posts, ratchet wheels on the shafts, and pawls carried by certain of the posts and cooperating with the ratchet wheels.

2. A hay stacker comprising posts disposed in approximately parallel lines, means for connecting together the posts of each line, slides mounted at their ends for reciprocation on the posts of the respective lines, a track carried by the slides, shafts extended between the posts of each line and journaled

thereon, flexible elements connected at their ends to the shafts and to the slides, and guided intermediate their ends on the posts, means for rotating the shafts, and means for preventing retrograde rotation of the shafts.

In testimony that I claim the foregoing as my own, I have hereto affixed my signature in the presence of two witnesses.

JAMES H. MILLER.
